The ornamental design for a beach towel stake, as shown.

DESCRIPTION

FIG. 1 is a front top and side perspective view of a beach towel stake showing our new design;

FIG. 2 is a rear elevational view;

FIG. 3 is a front elevational view;

FIG. 4 is a right side elevational view;

FIG. 5 is a top plan view; and,

FIG. 6 is a bottom plan view.

The left side of the beach towel stake is a mirror image of the right side.

FIG. 1

FIG. 2

FIG. 3

FIG. 4

FIG. 5

FIG. 6
